[57] ABSTRACT

A device for conveying objects from one point to another, such as for conveying football practice dummies, may be yieldably suspended from a track or cable, and may yieldable, movable target, as the carriage carries the dummy longitudinally on the cables, one end of the cables may be selectively altered, as well as yieldably maintained at a preselected plane. A modification of the device providing means for transporting a carriage over an extended area, providing posts intermediate of the vertical adjustable post and the fixed post, having cable connectors permitting passage of the carriage on the cables over the post.

CONVEYOR FOR FOOTBALL TACKLING DUMMIES

SUMMARY OF THE INVENTION

A conveyor for moving an object from one point to another having a fixed position and a vertically adjustable position, with a vertically yieldable support extending from said adjustable position and novel means for avoiding friction in such adjustment, and a carriage on said cables having means for easy antifriction movement thereon and for transverse movement of the object carried by said carriage and a modified structure for continuous conveyance of the carriage over support poles.

BRIEF DESCRIPTION OF THE DRAWINGS

FIG. 1 is an elevational view, in perspective, of the device with a football dummy being carried thereby.

FIG. 2 is a cross-sectional elevational view of a support pole, taken on the line 2—2 of FIG. 1.

FIG. 3 is a cross-sectional end view of the antifriction means employed, taken on the line 3—3 of FIG. 2.

FIG. 4 is an elevational end view, in cross section, taken on the line 4—4 of FIG. 1.

FIG. 5 is an elevational cross-sectional side view of the carrier, taken on the line 5—5 of FIG. 4.

FIG. 6 is an elevational cross-sectional view taken on the line 6—6 of FIG. 4.

FIG. 7 is an elevational cross-sectional view of a modified form of carriage and cable support, and

FIG. 8 is a cross-sectional, elevational view, taken on the line 8—8 of FIG. 7.

DESCRIPTION OF THE PREFERRED EMBODIMENTS

In the drawings, the numerals 1, 1' designate posts seated in postholes formed in concrete foundations, as 2, in the earth 3. A collar 4 is seated in the foundation and has a hinged line 5 thereon, which may be employed to close the opening when the post is removed for use at another location.

The post 1 is tubular, and has the telescoping member 6 mounted therein, which consists of the angle irons 7, 7 mounted on an extension as 8, with the wheels 9, 9 mounted between the angle irons 7, 7 and extending outwardly from the extended margins thereof, in contact with the post 1, which is rotatable by means of the crank 11, and a line 12 leads from the winch to the bottom of the telescoping member 6, and a coil spring as 13 rests on the internal flange 14 at one end, the other end of which bears against the lower end of the member 6.

Multiple cables, as 15, extend from the crossarm 16, mounted on the upper end of the extension 8, to the other post as 1', which may be of integral sections and terminates with a crossarm 16' and the cables 15 extend through suitable ports in the crossarm 16' and have a stop formed on the extended ends of the cables 15 against which the washers 61 bear, and coil springs 62, 62 abut said washers at one end and the crossarm 16' at the other end, making the cables 15 yieldable, as the extension 8 in the post 1 moves vertically, and a carriage 17 reciprocates on the cables between the posts 1 and 2, the cables 15, 15 extending through the carriage 17 and the carriage being mounted on the cables 15, 15 by means of the mounts formed by securing one set of angle irons, as 18, 18 to the carriage as by welding one margin of the uppermost set thereof to the carriage framework and securing another set of angle irons 19, 19 to the fixed set as by means of suitable bolts (not shown) said bolts extending through the abutting walls of the angle iron sets 18, 19 and spaced apart to permit free rotation of the rollers 20, 20 mounted between said walls, said rollers having a concave bearing surface in contact with the cables 15, 15.

Integral with the carriage 17 is the transverse carriage housing 21 which is tubular and has the downwardly extended skirts 22, 22 extending from the margins of the longitudinal slot 23. Antifriction rollers 24, 24 are transversely mounted in the skirts 22, 22 and are of sufficient diameter to bear against

and steady the hanger 25 as it reciprocates in the housing 21. A rod, or track, 26, extends axially and longitudinally in the housing 21. Yieldable members, such as the springs 27, 27 are mounted in the housing 21 adjacent the respective ends 5 thereof, and against which the hanger 25 bears as it moves longitudinally in the housing 21.

The hanger 25 has the angle iron tracking means 28 having the rollers 29 thereof riding on the bar 26. Caps 30, 30 close the housing 21, and permit selective changing of the springs 10 27 to alter the resistance against the hanger 25, as desired.

Pivottally suspended from the hanger 25 is a tackle dummy support 31 which has a transverse tubular spring housing 32 and which has the downwardly extending integral tubular section 33 which when the dummy is being used for a blocking dummy, telescopes into the reinforcing member 34, which is of less outside diameter, and therefor may be selectively mounted in the hard rubber connecting section 35. Bolt holes, as 36, 36, in the section 33, receive the bolts 37, 37 when the tackle dummy is to be used as a blocking dummy, in which case the member 34, which is a rigid metal tube, is lowered into the section 35, after the bolts 37 are removed from the section 35, and when the bolt holes 31 are in alignment with the bolt holes in the section 35, the bolts are again inserted 20 therein, deactivating the spring 37'. The spring 37' is anchored at one end to the rotatable rod 38 in the housing 31 and at its other end to the housing 31, a line 39 is secured at one end to the rod 38, and at its other end to the bolts 37, such as by means of an eyelet 40. When being used as a tackle dummy, the reinforcing member 34 is removed and the bolts 37 are mounted in the section 35 and the line 39 secured to said bolts, and when the user hits the dummy, the dummy is forced down, the spring 37' is wrapped around the rod 38 and placed under tension, and when the user releases the dummy, the 25 spring will rotate the rod 38 and return the section 35 to the section 33, the outwardly flared ends of the section 35 guiding the end of the section 33 into the section 35. Washers 63, 63 may be mounted on the rod 38, enclosing the line 39, to prevent fouling with the spring 37'.

30 In operation, when used for football practice, the tackling dummy is suspended from the hanger 25, and the extension 8 is elevated to cause the carriage 17 to move by gravity towards the opposite post. As the carriage moves on the cables 15, the dummy will move transversely, and when reaching the end of 35 one transverse movement, will strike the spring at the end of the carriage housing and be urged in the opposite direction. As a player tackles the dummy, the force of the blow and the weight of the player, will be exerted against the spring 37, the section 35 traveling downwardly, and the spring 37 returning the section to its original position. As a load is applied to the dummy, the force will be applied to the cables 15 and post part 8, and the extension 8 will bear against the springs 13, absorbing the shock, and the spring 13 will return the extension 8 to its predetermined position and the hanger will continue its transverse movement. At the end of the trip of the carriage 17, the crank 11 may be manipulated to lower the extension 8 and cause the carriage to travel back to the post 2, by gravity, and the practice may continue. If desired, multiple carriages may 40 be mounted on the cables. Many other objects may be suspended from the section 33 in place of the tackling dummy, such as targets, or other objects to be transported from one place to the other.

65 In the modified form, shown in FIGS. 7 and 8, provision is made for making the movement of the carriage continuous, such as around a building, or other given area, and in this form, the carriage 41 rides on the cables 42 and the angle irons 43, 43 are anchored to the carriage by means of welding one margin to the inside wall of the carriage, and by bolting 55 the other irons 44, 44 (bolts not shown) to the anchored irons, and by mounting wheels 45, 45 between the abutting walls of the angle irons 43, 44.

70 Mounted on top of the post 46 is the crossarm 47 on which channel irons as 48 are fixedly mounted, one channel iron for each cable 42, and threaded adjusting shafts 49, 49 are

mounted in said members 48 and bear against the cable connectors 50, which consist of the cable end receiving member 51, which is tubular and has the internal teeth 52, and an internal flange in the cable receiving member provides a stop for the swivel sleeve 54, pivotally mounted to the shaft 55, said shaft extending through the bore in the upper portion of the member 50. The extended end of the shaft 55 is externally threaded and mounted on the threaded end thereof is the adjusting member 56, which is internally threaded and has a portion of its external surface squared as at 57 to receive a wrench for rotation, and the extended end of said member has the cable clamp 58 which will receive the end of the next section of cable. The shafts 48 adjust the connector 50 transversely in the channel members 48. Friction wheels as 63 mounted in the downwardly extending walls of the irons 44, 44 bear against the outside walls of the connector 50, stabilizing the movement of the carriage over the posts 46.

Where it is desired to move the carriage over great areas or around a building, the carriage passes over the posts 46, riding on top of the cables 42. One end of the cable section is anchored to the adjusting post, and the other end compressed and inserted into the receiving member 51; the adjusting member 56 is then rotated until the cable 42 is tight, then the members 51 and 56 are anchored to the members 48 by welding, filling in the area between the respective members 51, 56 and the member 48, as shown at 59, 59. The end of the next section of cable 42 is then clamped to the swivel 58 and the operation repeated until the construction is completed.

As the carriage 41 moves over the cables 42, it will be free to travel continuously over the great areas or around a building, the wheels 45 riding on the cables 42 and the connectors 50 when passing over the supporting, intermediate posts 46, with the friction wheels 63 bearing against the sidewalls of the connector 50.

The carriage, when so used, may be of sufficient strength to transport people, or workmen and their equipment, and such a carriage may be moved by gravity, by placing the vertically adjustable post in alternate relation with the fixed post, or the carriage may be equipped with self-powering equipment, one or more of the wheels being rotated.

What I claim is:

1. A conveyor having a cable supported carriage, cables yieldably mounted to a fixed post at one end and secured to a vertically adjustable post at the other end, cable mounting

means in said carriage having wheels rotatably mounted therein and bearing against said cable, and having a transverse tubular housing mounted thereon, a rod longitudinally mounted in said transverse housing, and a carrier mounted on said rod, coil springs mounted in said transverse housing adjacent each end thereof forming a yieldable stop for said carrier, and an object to be carried pivotally suspended from said carrier.

2. The device defined in claim 1 wherein there is suspended from said carrier a shock absorbing means, from which said means the object to be carried is suspended, said shock absorbing means consisting of a pair of tubular sections, one section being pivoted to said carrier and having a transverse tubular spring housing, a rotatable rod longitudinally mounted in said spring housing, and a coil spring anchored at one end to said housing and at the other end to said rod, the other section having bolts mounted transversely therein adjacent one end and a line having one end mounted on said rod and the other end anchored to the object to be carried, said line rotating said rod when a shock is applied to said object being carried, applying tension to said spring and said spring rotating said rod in the opposite direction when said shock is relieved, returning said object to its original position.

3. The device defined in claim 2 having a rigid reinforcing member insertable into the object to be carried and anchored to the first mentioned section.

4. The device defined in claim 3 having antifriction members mounted on said cable connectors upon which the carriage bears as it passes over said cable connectors.

5. A conveyor having a cable supported carriage, cables yieldably mounted to a fixed post at one end and secured to a vertically adjustable post at the other end, cable mounting means in said carriage having wheels rotatably mounted therein and bearing against said cable, intermediate posts between the adjustable and fixed cable ends, a cross member on said posts having upstanding cable connectors, said connectors having a cable end receiving chamber and a rotatable shaft having one end mounted in said chamber and the other end extending through said upstanding cable connector, said last-mentioned end being externally threaded, an adjusting member internally threaded and mounted on said threaded end of said shaft, and a cable end receiving member formed in the extended end of said adjusting member.
